(57) **CLAIM**

The ornamental design for a combination communication device and a support bracket, as shown and described.

DESCRIPTION

FIG. 1 is a perspective view of a combination communication device and support bracket showing my new design, wherein the support bracket has been removed for clarity and completeness of disclosure;

FIG. 2 is another view thereof;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is bottom view thereof;

FIG. 9 is a perspective view of the combination communication device and support bracket of FIG. 1, wherein the communication device and support bracket are shown connected for clarity and completeness of disclosure;

FIG. 10 is another view thereof;

FIG. 11 is a front view thereof;

FIG. 12 is a back view thereof;

FIG. 13 is a side view thereof;

FIG. 14 is another side view thereof;

FIG. 15 is a top view thereof;

FIG. 16 is bottom view thereof;

FIG. 17 is a perspective view of the combination communication device and support bracket of FIG. 1, wherein the communication device has been removed for clarity and completeness of disclosure;

FIG. 18 is another view thereof;

FIG. 19 is a front view thereof;

FIG. 20 is a back view thereof;

FIG. 21 is a side view thereof;

FIG. 22 is another side view thereof;

FIG. 23 is a top view thereof; and,

FIG. 24 is bottom view thereof.

The broken lines shown in the drawings illustrate portions of the combination communication device and support bracket that form no part of the claimed design.
